UNITED STATES PATENT OFFICE

SAMUEL J. CAMPBELL, OF GREEN BAY, WISCONSIN, ASSIGNOR TO HUDSON-SHARP MACHINE COMPANY, OF GREEN BAY, WISCONSIN, A CORPORATION OF WISCONSIN

FOLDING AND SCALLOPING MACHINE

Application filed October 30, 1929. Serial No. 403,385.

The machine of the present invention is designed to continuously feed forward a strip or web of paper, preferably tissue paper, and to cut therefrom lengths or sections which are twice folded to square formation and are thereupon scalloped while in the folded condition, and packed into a stack for ultimate shipment.

By arranging the scalloping dies to act upon two meeting edges of a twice-folded paper napkin or the like, the scalloping will extend continuously around the entire margin of the napkin when unfolded, and the present invention is particularly designed to correlate the scalloping and packing mechanisms so that these two operations will be simultaneously performed after the folding is completed.

Further objects and details will appear from a description of the invention in conjunction with the accompanying drawings, wherein

Fig. 1 is a view of a sectional elevation through the center of the machine;

Fig. 2 is a sectional detail showing the scalloping dies, the packer and associated mechanisms;

Fig. 3 is a view of the same at right angles to Fig. 2;

Fig. 4 is a side elevation of the machine, showing the packing and scalloping mechanism partly in section;

Fig. 5 is a view of the twice folded napkin; and

Fig. 6 is a view of the completed napkin in unfolded relation.

The machine, as a whole, comprises end frames 10 and 11, each of which is provided with upwardly extending arms 12 and 13, and downwardly extending legs 14. The end frames are connected by lower tubular cross connections 15 and upper tie rods 16, which serve to rigidly secure the end frames together into a unified frame structure.

The upper arms 12 and 13 serve to support top rails 17 which are extended to afford brackets 18-18 which serve to journal the paper rolls 19-19, the machine being constructed in duplicate to simultaneously feed two paper webs to the folding, scalloping

and packing mechanisms now to be described.

In view of the fact that the parts are arranged in duplicate, a description of one end of the machine will suffice for both.

The paper web from one of the paper rolls 19 is fed over a guide roller 20 and thence down over a triangular obliquely disposed plate, constituting a former 21 which gives to the paper web a longitudinal fold, the once-folded paper passing between draw rollers 22-22 below the former. From the rollers 22, the once-folded web is carried through cutting rollers 23-23 and thence in front of an endless tape 24, carried over rollers 25 and 26 and in contact with a tension roller 27.

An oscillating folder blade 28 is mounted for reciprocation across the path of the paper as it is carried down between the tape 24 and a companion tape 29 mounted on rollers 30-30.

The oscillating folder blade is carried by an arm 31 carried by a rock shaft 32, the operation of the folder being so timed as to engage the center of a once-folded paper web section at the instant the same is severed by the cutting rollers 23-23, so that at this instant the severed web section will be carried laterally by the folder blade into the bite of upper and lower folding rollers 33 and 34, the first of which mounts an endless tape or belt 35, the inner turn of which engages the folding roller 34. The belt or tape passes around the upper roller 33 and a guide roller 36, the parts being so arranged and timed that the once-folded paper section engaged by the folder blade will be caught between the bite of the rolls 33 and 34 and carried under the tape or belt 35 to impart the cross fold to the napkin or other article.

The twice-folded napkin will be fed down between lips 37 and 38 which lie in spaced relation and serve to feed the twice-folded napkin in front of a reciprocating plunger 39 mounted upon a base plate 40 and actuated by a plunger rod 41.

The plunger is of substantially square configuration, as shown in Fig. 3, and is provided around two of its converging edges with scallops or undulations 42 which constitute a male scalloping die, the metal along these

edges being rearwardly extended to furnish a marginal reinforcing flange 43 behind the die portion of the plunger.

The plunger cooperates with a female die 5 in the form of an angularly configured frame 44 having around its two converging inner edges a scalloped flange 45 which constitutes the female die with which the plunger cooperates. The die, as a whole, is suitably 10 mounted upon the base plate 40 and supported from above by a bracket frame 46, or in any other suitable manner.

In order to guide the twice-folded napkins between the dies when in the open or retracted position shown in full lines in Fig. 15 2, guide fingers 47 are provided which extend upwardly through slots 48 in the base plate 40, and, when elevated, stand in spaced relation to the plunger in its retracted position. Each of the fingers is provided with 20 rack teeth 49 which engage with a spur pinion 50 operated by a toothed segment 51 carried by a rock shaft 52 having keyed thereon a crank arm 53 which is actuated by a rod 25 54. These parts are suitably timed so that as the plunger advances to bring the die members into co-active relation, the fingers will recede as the napkin is packed out.

Behind the female die is located an elongated trough 55 which receives the quarter-folded napkins as they are packed out, a weight 56 or other suitable resistance member being located within the trough to maintain the quarter-folded napkins in stack formation as they are forced from the dies and into the trough.

In operation, the paper web is fed continuously from the roll and down over the former and through the draw rollers and cutting rollers. As the cutting rollers rotate, 40 they will measure off sections of the once-folded web and sever the same at the instant the folder blade advances to transversely engage the leading section preparatory to initiating a cross fold in it.

Thereafter, the folder blade will move forwardly and thrust the paper section into the folding rollers 33—34 which complete the fold and deliver the quarter-folded napkin between the scalloping dies with the free or raw edges extended around two sides of the quarter-fold and in position to be engaged by the dies.

As soon as the quarter-folded napkin is 55 thus positioned, the plunger will advance simultaneously with the retraction of the guide fingers 47 so that the raw edges of the quarter-folded napkin will be cut by the dies and given a scalloped configuration, the trimmings being removed and discharged by a pneumatic blast or other suitable means for removing the waste. The plunger will advance sufficiently to discharge the quarter-folded napkin against the resistance of the 60 stack of folded napkins in advance, and there-

after the series of operations will be repeated in continuous succession.

The machine, as a whole, is simple in construction, and by reason of the unification of the scalloping mechanism with the packer, it 70 is not necessary to provide independent scalloping mechanism for action on the paper during a preliminary stage in the feeding operation.

Furthermore, by the provision of scalloping dies which are arranged to act upon the napkin in its twice-folded condition, the length or extent of the dies is reduced, since by a single operation four plies of paper are 75 simultaneously scalloped, which completes 80 the marginal scalloping all the way around the napkin.

Furthermore, although the term "napkin" has been employed as a convenient designation for the article folded and scalloped 85 by the present machine, it will be understood that the machine is applicable for use in the folding or scalloping of other articles of paper or fabric, irrespective of the use 90 for which they are ultimately intended.

Although the invention has been described in particular detail, it is not the intention to limit the same, save as indicated in the claims, since variation in structure may be introduced without departing from the spirit 95 of the invention.

I claim:

1. In a machine of the class described, the combination of means for folding an article, scalloping dies located at the discharge end 100 of the folding means, and means for actuating the scalloping dies after delivery of the folded article to scallop and discharge the same.

2. In a machine of the class described, the combination of means for folding an article, scalloping dies located at the discharge end of the folding means, means for actuating the scalloping dies after delivery of the folded article to scallop and discharge the 105 same, a guide finger coacting with the scalloping dies to position the folded article in advance of the scalloping operation, and means for retracting the guide finger as the scalloping operation is initiated.

3. In a machine of the class described, the combination of means for folding an article, scalloping dies located at the discharge end 110 of the folding means, means for actuating the scalloping dies after delivery of the folded article to scallop and discharge the same, a guide finger positioned to receive the folded article between the scalloping dies, the guide finger being provided with rack teeth, and a pinion meshing therewith to 115 retract the guide finger as the scalloping operation is initiated.

4. In a machine of the class described, the combination of means for longitudinally folding an article, means for transversely 120

5 folding the longitudinally folded article to produce a quarter-folded article, male and female scalloping dies configured to act upon two converging edges of the quarter-folded article, means for advancing the male die member to co-act with the female die member in scalloping the quarter-folded article and in discharging the same.

10 5. In a machine of the class described, the combination of means for longitudinally folding an article, means for transversely folding the longitudinally folded article to produce a quarter-folded article, male and female scalloping dies configured to act upon two converging edges of the quarter-folded article, means for advancing the male die member to co-act with the female die member in scalloping the quarter-folded article and in discharging the same, and a trough 20 located behind the female die member and adapted to receive the discharged quarter-folded articles in stack formation.

25 6. In a machine of the class described, the combination of means for longitudinally folding an article, means for transversely folding the longitudinally folded article to produce a quarter-folded article, male and female scalloping dies configured to act upon two converging edges of the quarter-folded article, means for advancing the male die member to co-act with the female die member in scalloping the quarter-folded article and in discharging the same, a reciprocating guide finger located in co-acting relation 30 with the female scalloping die and adapted to position the quarter-folded article between the dies, and means for retracting the finger as the male die advances.

35 7. In a machine of the class described, the combination of means for longitudinally folding an article, means for transversely folding the longitudinally folded article to produce a quarter-folded article, male and female scalloping dies configured to act upon two converging edges of the quarter-folded article, means for advancing the male die member to co-act with the female die member in scalloping the quarter-folded article and in discharging the same, a trough located behind 40 the female die member and adapted to receive the discharged quarter-folded articles in stack formation, a reciprocating guide finger located in co-acting relation with the female scalloping die and adapted to position the quarter-folded article between the dies, and means for retracting the finger as the male die advances.

45 8. In a machine of the class described, the combination of means for longitudinally folding a web of material, means for severing sections of the once-folded web, a folder blade for initiating a cross fold in the once-folded and severed section, folding rollers for completing the cross fold, male and female scalloping die members normally standing in separated relation and in position to receive the quarter-folded article to effect the scalloping operation.

50 9. In a machine of the class described, the combination of means for longitudinally folding a web of material, means for severing sections of the once-folded web, a folder blade for initiating a cross fold in the once-folded and severed section, folding rollers for completing the cross fold, male and female scalloping die members normally standing in separated relation and in position to receive the quarter-folded article from the folding rollers, means for advancing the male die to effect the scalloping operation, a guide finger normally standing in opposed relation to the male die, and means for retracting said guide finger as the male die advances.

55 10. In a machine of the class described, the combination of means for longitudinally folding a web of material, means for severing sections of the once-folded web, a folder blade for initiating a cross fold in the once-folded and severed section, folding rollers for completing the cross fold, male and female scalloping die members normally standing in separated relation and in position to receive the quarter-folded article from the folding rollers, means for advancing the male die to effect the scalloping operation, a guide finger normally standing in opposed relation to the male die, and means for retracting said guide finger as the male die advances.

60 11. In a machine of the class described, the combination of means for longitudinally folding a web of material, means for severing sections of the once-folded web, a folder blade for initiating a cross fold in the once-folded and severed section, folding rollers for completing the cross fold, male and female scalloping die members normally standing in separated relation and in position to receive the quarter-folded article from the folding rollers, means for advancing the male die to effect the scalloping operation, and a trough located behind the female die member and adapted to receive the folded and scalloped articles in stack formation.

65 12. In a machine of the class described, the combination of means for longitudinally folding a web of material, means for severing sections of the once-folded web, a folder blade for initiating a cross fold in the once-folded and severed section, folding rollers for completing the cross fold, male and female scalloping die members normally standing in separated relation and in position to receive the quarter-folded article from the folding rollers, means for advancing the male die to effect the scalloping operation, a guide finger normally standing in opposed relation to the male die, means for retracting said guide finger as the male die advances, and a trough located behind the female die member and adapted to receive the folded and scalloped articles in stack formation.

70 13. In a machine of the class described, the combination of a former adapted to longitudinally fold a paper web, cutting rollers positioned to receive the once-folded paper web after its passage over the former and to sever sections therefrom, an oscillating folder blade adapted to initiate a cross fold in the once-folded paper section, folding rollers co-acting with the folder blade and adapted to receive the paper section therefrom and complete the cross fold, male and female scalloping dies located in position to receive the quarter-folded article.

from the folding rollers, said dies normally standing in separated relation and said dies being provided around two edges with cutting members adapted to impart the desired edge configuration to the edges of the quarter-folded article, and means for reciprocating the male die member.

13. In a machine of the class described, the combination of a former adapted to longitudinally fold a paper web, cutting rollers positioned to receive the once-folded paper web after its passage over the former and to sever sections therefrom, an oscillating folder blade adapted to initiate a cross fold in the once-folded paper section, folding rollers co-acting with the folder blade and adapted to receive the paper section therefrom and complete the cross fold, male and female scalloping dies located in position to receive the quarter-folded article from the folding rollers, said dies normally standing in separated relation and said dies being provided around two edges with cutting members adapted to impart the desired edge configuration to the edges of the quarter-folded article, means for reciprocating the male die member, a guide finger normally standing in opposed relation to the male die member, and means for retracting said guide finger before the advance of the male die member.

14. In a machine of the class described, the combination of a former adapted to longitudinally fold a paper web, cutting rollers positioned to receive the once-folded paper web after its passage over the former and to sever sections therefrom, an oscillating folder blade adapted to initiate a cross fold in the once-folded paper section, folding rollers co-acting with the folder blade and adapted to receive the paper section therefrom and complete the cross fold, male and female scalloping dies located in position to receive the quarter-folded article from the folding rollers, said dies normally standing in separated relation and said dies being provided around two edges with cutting members adapted to impart the desired edge configuration to the edges of the quarter-folded article, means for reciprocating the male die member, and a trough located behind the female die member and adapted to receive the quarter-folded articles therefrom in stack formation.

15. In a machine of the class described, the combination of a former adapted to longitudinally fold a paper web, cutting rollers positioned to receive the once-folded paper web after its passage over the former and to sever sections therefrom, an oscillating folder blade adapted to initiate a cross fold in the once-folded paper section, folding rollers co-acting with the folder blade and adapted to receive the paper section therefrom and complete the cross fold, male and female scalloping dies located in position to

receive the quarter-folded article from the folding rollers, said dies normally standing in separated relation and said dies being provided around two edges with cutting members adapted to impart the desired edge configuration to the edges of the quarter-folded article, means for reciprocating the male die member, a guide finger normally standing in opposed relation to the male die member, means for retracting said guide finger before the advance of the male die member, and a trough located behind the female die member and adapted to receive the quarter-folded articles therefrom in stack formation.

16. In a machine of the class described, the combination of means for twice folding an article, male and female cutting dies located at the discharge end of said folding means and in position to receive a quarter-folded article delivered therefrom and normally standing in separated relation to one another, and means for advancing one of said dies into cutting relation with the other.

In witness that I claim the foregoing I do have hereunto subscribed my name this 24th day of Oct., 1929.

SAMUEL J. CAMPBELL.
